LABEL SUPPORT

Thomas H. Golden, Pottsville, Pa., assignor to
Phillips-Jones Corporation, New York, N. Y., a
corporation of New York

Application April 25, 1933, Serial No. 667,799

3 Claims. (Cl. 40—26)

This invention relates to packages for garments and more particularly to packages for men's apparel such as men's shirts. In packaging such products it is important that the garments present a neat and attractive appearance, and in the case of men's shirts where they are provided with attached collars having some particular feature to which it is desired to draw attention by means of a label, the attachment of the label 5 without detracting from the appearance of the package as a whole presents something of a problem. The label cannot be attached to the collar directly without a tendency to interfere with the makeup of the package as a whole. Moreover, 10 the label cannot be attached to the shirt front by means of pins, or other fastening devices which pierce the material of the garment, without leaving an objectionable mark in a place where it will be visible as soon as the label is 15 removed by the wearer.

It is the principal object of the present invention to provide a label support which can be attached to the shirt without the use of pins or the like, which will stay securely in place during 20 the ordinary handling of the garment up to the time of sale, and which can be readily removed by the purchaser.

Another object of the invention is to provide 25 a label support for attachment to the front of a shirt adjacent the shirt collar which is so arranged that the principal mechanical features for attaching the device are concealed from view.

The packaging of shirts is not an unimportant item in the gross manufacturing cost of the product, and it is therefore necessary, in view of the 30 fact that the placing of the label constitutes an additional operation to be performed during the packaging, that the label be placed in position with a minimum amount of time and effort. Accordingly, another object of the invention is to 35 provide a label support which is so constructed that it can be readily attached to the shirt with little manipulation, and without the necessity of applying any external fastening means.

40 My invention will be understood from a consideration of the accompanying drawing which shows by way of example several embodiments thereof. In the drawing:

45 Fig. 1 represents a front view of a folded shirt with my improved label support in position thereon;

Fig. 2 represents a front view showing the construction of the label support shown in Fig. 1;

50 Fig. 3 represents a view similar to Fig. 1 of the

upper portion of a shirt having a modified form of label support in position thereon;

Fig. 4 represents a front view similar to Fig. 2 of this modified label support;

Figs. 5 and 6 are views illustrating an additional modification of the label support.

Referring now to Fig. 1 of the accompanying drawing, the shirt 1 is folded in the usual manner with the shirt front flat and the cuffs pinned flat against the lower portion of the shirt bosom. 65 The shirt is provided with an attached collar 2 having projecting front points 3 and 4, and it will be understood that this collar possesses certain unusual features to which it is desired to attract the prospective purchaser's attention.

70 The label 5 which is intended to set forth these features of the collar is placed upon the body portion 6 of a label support 7 which consists of a piece of sheet material such, for example, as paper of suitable weight and quality.

75 In order to secure the label support 7 in place upon the bosom of the shirt it is provided with an arch-like portion or formation 8 having sides 9 which extend upwardly from the upper edge of the body portion 6. An aperture 10 lies between the sides 9 of arch-like portion 8, and in the particular construction shown in the drawing extends downwardly into the body portion 6. A slot 11 is formed in the upper part of aperture 10 into which the collar button 12 of the 85 shirt collar is adapted to be received.

80 The frictional engagement of the collar button with the surface of the material adjacent slot 11 is sufficient to hold the upper part of the label support in place, and in order to secure the lower part of the label support in position, the body 6 thereof is preferably provided with a second button slot 13, into which one of the buttons on the shirt front is adapted to be received, for example, the button 14. In order to provide 90 added security, the inner margins of aperture 10 are formed with a pair of oppositely projecting tongues 15 which are slipped under the edges of the opposite side edges of the center plait 16 on shirt 1.

95 This label support may be readily placed in position on the buttons 12 and 14 by lifting the points 3 and 4 of the collar and engaging the slots 11 and 13 with the respective buttons, and then giving the device a slight downward movement, the tongues 15 being tucked beneath the edges of the center plait. The width of the material between the upper end of slot 11 and the edge of the arch-like portion 8 is less than the 100

100

105

110

distance from the edge of the button 12 to the throat 17 of the collar so as to facilitate the placing of the label support on button 12, although after the label support is in position the friction 5 of the upper edge of the arch-like portion 8 with the surface of the collar band aids in preventing dislodgment of the label support. The label support is prevented from being displaced laterally by means of the button 14 and the button 10 slot 13 and also by means of the tongues 15. The tongues 15 also provide an appreciable degree of friction with the under surfaces of center plait 16 which materially assist in preventing the upward movement of the label support which would 15 disengage it from the buttons.

The sides 9 of the arch-like portion 8 are shaped so as to be substantially concealed by the points 3 and 4 of the collar, leaving the body 6 of the label support exposed immediately below the collar 20 and lying flat against the front of the shirt. The placing of the tongues 15 beneath the center plait 16 leaves the upper portion of the center plait exposed to the full view of the purchaser through the aperture 10.

25 Referring now to Figs. 3 and 4 of the accompanying drawing, the modified form of label support here illustrated is intended for shirts which do not have a center plait, such, for example, as the shirt shown at 18. The label support 7a has 30 a body portion 6a and an arch-like portion 8a of about the same configuration as shown in Figs. 1 and 2. The aperture 10a, however, is somewhat wider, the tongues 15 being omitted and the left-hand edge 19 substantially meeting the overlapping edge 20 of the shirt so as to expose a strip 35 of the shirt front within the center of the label support of about the same width as the center plait 16.

40 Aperture 10a is somewhat shorter and does not extend into the body portion 6a of the support, but it can be made to extend down into the body portion if desired. The label support 7a is held in position entirely by means of the button slots 11a and 13a into which are engaged respectively 45 the collar button and the uppermost button of the shirt front. As in the case of label support 7, the arch-like portion 8a is substantially concealed from view by the points of the collar.

45 In the modified form of label support 7b shown 50 in Figs. 5 and 6, which, like label support 7, is intended for use with shirts having a center plait 16, the support is held in position by means of button slot 11b which engages the collar button and by the tongues 15a which engage the margins 55 of the center plait 16. The button slot at the bottom of the body portion 6b is omitted, and the tongues 15a serve adequately to prevent the lateral displacement of the label support. The friction 60 of these tongues with the under sides of the center plait is sufficient to prevent the upward displacement of the label support and the disengagement of the button slot 11b from the collar button.

65

70

75

The embodiments of the invention above described merely serve to illustrate the invention and changes may be made in the label support without departing from the invention, the scope of which is defined in the appended claims.

80 It will be understood that my improved label support affords a way of neatly and quickly securing to a shirt front an attractive label which adds to the neatness and smartness of the shirt package as a whole, this label support being of particular utility where the shirt is provided with an attached collar having characteristics to which the label directs attention. In meeting this need the arrangement of the parts of the label support is such as to conceal from view beneath the points of the collar the principal mechanical features of the support by means of which the support is held in place on the garment.

85 I claim:

90 1. In a shirt package including a shirt having the overlapping margins of the front thereof buttoned together and folded flat, said shirt having a center plait, in combination, a label support of sheet material, having a pair of spaced button slots opening in the same direction for engaging 95 two of the shirt buttons to hold said support in position on the front of the shirt, said support having an aperture therein provided with a pair of tongues extending toward one another from the side margins of said aperture and adapted to 100 frictionally engage the under surfaces of the margins of said center plait to aid in preventing the disengagement of said button slots from the said buttons.

105 2. In a shirt package including a shirt having a center plait and folded so that the upper portion of the shirt front is flat, said shirt having a collar attached thereto, in combination, a label support of sheet material having a body portion for supporting the label, and a projection extending from 110 the upper edge of said body portion beneath the points of the collar and having a slot at the top thereof into which the collar button is received, and a pair of tongues on said label support projecting toward one another and adapted to be 115 positioned beneath the opposite said edges of said center plait so as to prevent lateral displacement of said support.

120 3. In a shirt package including a shirt having a center plait and folded so that the upper portion 125 of the shirt front is flat, said shirt having a collar attached thereto, in combination, a label support of sheet material having a body portion for supporting the label, and a projection extending from 130 the upper edge of said body portion beneath the points of the collar and having a slot at the top thereof into which the collar button is received, a pair of oppositely projecting tongues on said 135 label support engaging beneath the side margins of said center plait, and the body of said label support having means thereon for engaging a button on the front of the shirt.
